UNITED STATES PATENT OFFICE.

GEORGE PORTUNE, OF CINCINNATI, OHIO.

BOOK-COVER PROTECTOR.

1,172,045.

Specification of Letters Patent. Patented Feb. 15, 1916.

Application filed April 6, 1915. Serial No. 19,492.

To all whom it may concern:

Be it known that I, GEORGE PORTUNE, a citizen of the United States, residing at Cincinnati, in the county of Hamilton and State of Ohio, have invented certain new and useful Improvements in Book-Cover Protectors; and I do hereby declare the following to be a full, clear, and exact description of the invention, such as will enable others skilled in the art to which it appertains to make and use the same.

This invention relates to book protectors for the backs and covers of books, and one of the principal objects of the invention is to provide a simple protector of fabric or tape or strong paper, and in different sizes, said protector having pockets at the corners for receiving the corners of the cover of the book, thus providing a protector which is easily connected to the book, and which will extend entirely over the back and cover of the book.

The foregoing and other objects may be attained by means of the construction illustrated in the accompanying drawing, in which—

Figure 1 is a plan view of the protector having one of its corners shown in plan before it is folded over to form the corner pocket, Fig. 2 is a detail plan view of one of the corner pockets partially folded, and Fig. 3 is a perspective view of one of the corner pockets pulled outward to admit the corner of the protector of a book.

Referring to the drawing, the numeral 1 designates the body portion of the book protector and this may be made of cloth, strong paper, vellum or tracing linen, and may be of different sizes for different characters of books. The protector 1 at each of the four corners is provided with an extended por-

tion 2, the corner 3 of which is adapted to be folded on the dotted line 4 and secured to the extension 2 by means of an adhesive substance 5. A flap 6 is folded on the dotted line 7, and the reverse side thereof is provided with an adhesive substance 8. When the corner is folded on the line 9 the adhesive substance 8 is connected to the body portion 1 of the protector, thus providing an open corner pocket, as shown in Fig. 3 to receive the corner of the cover of the book. Reinforcing strips 10 are formed on the cover 1 by folding portions of the cover upon itself to reinforce the edges of the cover 1 to prevent tearing and fraying during continuous usage.

From the foregoing it will be obvious that a book protector made in accordance with this invention can be produced cheaply, and can be quickly connected to the book.

Various changes may be made in the details of construction without departing from the spirit and scope of the invention as defined in the claim.

What is claimed is:—

A book cover protector comprising a rectangular body, rectangular extended portions at the corners of and overlying the body, one corner of each extended portion being folded upon and glued to the extended portion, flaps carried by the extended portions and glued to the body, said extended portions and body forming pockets adapted to receive the corners of a book cover.

In testimony whereof I affix my signature in presence of two witnesses.

GEORGE PORTUNE.
